UNITED STATES PATENT OFFICE.

ALBERT BALL, OF CLAREMONT, NEW HAMPSHIRE, ASSIGNOR TO
SULLIVAN MACHINERY COMPANY, OF CLAREMONT, NEW HAM-
SHIRE, A CORPORATION OF NEW HAMPSHIRE.

SUPPORT FOR DRILLS OR THE LIKE.

No. 823,662.

Specification of Letters Patent.

Patented June 19, 1906.

Application filed December 16, 1904. Serial No. 237,111.

To all whom it may concern:

Be it known that I, ALBERT BALL, a citizen of the United States, residing at Claremont, in the county of Sullivan and State of New Hampshire, have invented an Improvement in Supports for Drills or the Like, of which the following description, in connection with the accompanying drawings, is a specification, like letters on the drawings representing like parts.

My invention consists in improvements in supports for drilling-machines or the like, being more particularly intended, as is the illustrative embodiment thereof herein shown, for supporting the columns upon which are mounted drills employed in tunnel-work.

My invention will be best understood by reference to the following description, taken in connection with the accompanying illustration of one specific embodiment thereof, while its scope will be more particularly pointed out in the appended claims.

In the drawings, Figure 1 shows in elevation one form of my invention applied to a drill-column, the arm and drill-saddle being also shown as mounted upon said column. Fig. 2 is a section in elevation, partially broken away, taken through the foot and base of the column. Figs. 3 and 4 are views, in plan and elevation, respectively, of the column-foot. Fig. 5 is a plan of the base; Fig. 6, a plan of the cushioning-block. Fig. 7 shows a modification.

Referring to the drawings, I have there shown a column *a*, of ordinary form, carrying the usual arm *b* and drill-saddle *c*, adapted to receive the drilling-machine. The column here shown is surmounted by the cap *d*, provided with spurs adapted to sink into a yielding or cushioning substance, such as a block of wood *e*, which it is customary to interpose between the column and the roof of the heading or drift in which the drill is employed to give a more secure hold to the column and check the vibration thereof.

The column here shown is of the double-screw type, employing the screws *f*, resting upon the spurred steps *g*, the latter in turn being mounted upon a floor-block *h*, which herein, as usual, is also of wood. Engaging with the threads of the screws *f* is the base *i*, which supports the column, whereby the latter, as is usual, may be screwed and wedged

into position between the floor and the roof of the tunnel.

Referring more particularly to Figs. 1 to 6, inclusive, the column-base *i*, which is preferably of metal, is formed with a recess or cavity *j*, which may be of any suitable angular shape, inclosed by vertical walls, but which herein is substantially square. Preferably interposed between the column and the base and here lying within the cavity or recess is suitable cushioning means, herein consisting of the wooden block *k*, resting upon the spurs *l*, the latter formed in the base at the bottom of the cavity. Upon the cushioning-block *k* rests the column *a*, the part thereof in intermediate contact with the block being the foot *m*, herein provided with downwardly-pointed spurs, which like the spurs *l* sink into the face of the block when the column is in position and the screws *f* are tightened.

I have herein shown the foot end, Fig. 3, of a substantially square shape, adapted freely to enter the recess *j* and while fitting loosely therein prevented from turning by the inclosing walls thereof. This provides means through the interlocking walls of the foot and base positively to prevent the foot and the column attached thereto from turning relatively to the base. Other interlocking formations of the foot and base may evidently be employed; but the one described is both simple and effective. It has heretofore been common to mount the column-foot upon a wooden block; but the block has been bolted rigidly to the threaded base part and the spurred foot rigidly bolted to the block by a single central bolt. In the embodiment of my invention shown not only is the vibration of the column more effectively prevented, the block *k* being rigidly secured neither to the foot nor the base, but the column and its foot are removable from the base and free for withdrawal therefrom as soon as the screws *f* are turned to slack up on the pressure. Notwithstanding the fact that the foot is freely movable from the base, the column is positively prevented from turning by the interlocking formation given them. Thus when the column is in place and the drill is in use the vibration thereof is checked not only at the roof-block *e* and the floor-block *h*, but also at the block *k*. The column-foot is held against the latter only by the frictional con-

tact resulting from the compression of the screws, the turning of the column being prevented by the fit of the foot within the cavity.

5 The ready separation of the base of the column is a matter of great practical convenience, for it is customary in working headings to set up the drill as soon as enough of the blasted rock can be cleared to obtain a footing for the column. The column in its frequent transportations must be taken over the heaps of blasted stone every time it is set up, and this obviously can be accomplished with much greater ease and readiness when 15 separated from the heavy and cumbersome base than when attached thereto.

While I prefer the construction described for the reasons given, it will be obvious that even in the particular form of support shown 20 various changes may be made, while still attaining some or all of the objects of my invention.

By way of further illustration it may be possible to avoid the use of a positive interlocking formation between the base and the foot by some such construction as is illustrated in Fig. 7. There the foot may be round and capable of being turned within the cavity, while the spurs *n* are made large 25 enough to sink deeply into the wooden block, and the latter is enlarged approximately to fit the cavity, so as to prevent the splitting of the wood, and the grip thus obtained by the foot upon the base may be relied upon to prevent the column from turning, while still 30 leaving the latter, with the attached foot, free for withdrawal from the base.

It will be obvious that my invention is not limited to the particular embodiment or embodiments herein shown or to those suggested, but that its details may be varied within wide limits without departing from the spirit thereof.

I claim—

45 1. A double-screw column for a drilling-machine provided with a base having a cavity therein, a block resting upon the bottom of said cavity and a foot secured to said column said foot resting upon said block and 50 shaped to conform to the walls of said cavity.

2. In an apparatus of the class described,

the combination with a column having drill-supporting means thereon, of a base provided with a cavity, and cushioning means within said cavity extending to near the top thereof, 55 and a foot on said column adapted to engage said cushioning means and constructed to interlock with said base to prevent said column from turning with relation to the base.

3. In an apparatus of the class described, 60 the combination with a column having drill-supporting means thereon, of a base, cushioning means between said base and said column, and means positively to lock the parts to prevent the column from turning with relation to the base.

4. In an apparatus of the class described, the combination with a column, of a base upon which said column is mounted cushioning means between said column and said 70 base, and means positively to prevent said column from turning, said column being free for withdrawal from said base.

5. In an apparatus of the class described the combination with a column and base, a 75 cushioning-block between said base and said column, said column being free for withdrawal from the block and interlocking surfaces between said column and said block, thereby positively to prevent the former 80 from turning.

6. In an apparatus of the class described the combination with a column of a pair of adjusting-screws therefor, a base between said screws and upon which said column is 85 supported, and a cushioning-block loosely interposed between said column and said base.

7. In an apparatus of the class described the combination with a column member having drill-supporting means thereon of a base 90 member upon which said column member is supported, one of said members having a recess, and cushioning means within said recess and between said column and base members.

In testimony whereof I have signed my 95 name to this specification in the presence of two subscribing witnesses.

ALBERT BALL.
